(57) **CLAIM**

The ornamental design for a display screen or portion thereof with a group of graphical user interfaces, as shown and described.

DESCRIPTION

The FIGURE is a front view of a display screen or portion thereof with group of graphical user interfaces showing the claimed design.

The outermost broken lines in the FIGURE show a display screen or portion thereof, and form no part of the claimed design. The other broken lines in the FIGURE show portions of the group of graphical user interfaces that form no part of the claimed design.

1 Claim, 1 Drawing Sheet
